CONNECTICUT.

BURNISHING-MACHINE.

1,050,534.

Specification of Letters Patent. Patented Jan. 14, 1913.

Application filed December 5, 1911. Serial No. 664,065.

To all whom it may concern:

Be it known that we, CHARLES H. HART and GEORGE B. STRETCH, both citizens of the United States, and residents, respectively, 5 of Hartford, in the county of Hartford, and Meriden, in the county of New Haven, each in the State of Connecticut, have invented a new and Improved Burnishing-Machine, of which the following is a specification.

10 Our invention relates more especially to that class of devices employed for burnishing silverware and an object of our invention, among others, is to provide a machine of this class in which the burnishing operation may be performed in an extremely effective and expeditious manner.

15 One form of device embodying our invention and in the construction and use of which the object herein set out, as well as 20 others, may be attained is illustrated in the accompanying drawings in which—

Figure 1 is a view in vertical section through a machine embodying our invention, the holding arms located uppermost 25 being broken away. Fig. 2 is a view in vertical section on plane located at right angles to the plane of section of Fig. 1, two of the holding arms being removed and one being broken off. Fig. 3 is a detail view 30 in section showing the construction of the holders. Fig. 4 is a like view the plane of section being at a right angle to that of Fig. 3.

Our improved machine herein illustrated 35 and described embodies an apparatus in which the burnishing of an article may be performed at substantially a single operation, and in which the surface of the burnished article shall be uniform in appearance and free from marks, shades or the like.

In the accompanying drawings the numeral 6 denotes a base to which supports 7 are secured in any suitable manner, and in which supports a shaft 8 is journaled. 45 Holding arms 9 are secured to the shaft in any suitable number, the device herein illustrated having four extending in diametrically opposite directions, as shown in Fig. 1 of the drawings. These arms bear at 50 their ends holders for retaining the articles to be burnished, which holders may be of any suitable form and construction. In the form of holders shown herein a sleeve 10 is fitted to slide upon each arm for the 55 purpose of encircling an opening or slot 11

in each of said arms. An end of each sleeve has notches 12 formed on diametrically opposite sides and opposite the opening 11, a shoe 13 of copper or similar metal extending through each opening 11, each of which shoe has projecting parts 14 located in the notches and the thicker portions 15 of which extend within the sleeve as shown in Fig. 3 of the drawings. A rest 16 also formed of copper or like material is located within each opening 11 each rest having lips 17 to hold it in place, as plainly shown in Fig. 3 of the drawings. A lock nut 18 fits the threaded portion 19 of each arm to 70 press the sleeve against the article 21 located in the opening 20 and for the purpose of clamping it securely therein. The shaft is provided with a handle 22 or like means for rotating it to place articles supported by 75 the arms in any desired position, for the purpose of placing articles in and removing them from the holders, and for placing them in position to be subjected to the burnishing operation, a pin 23 being shown herein 80 as a means for locking the handle in place.

A burnisher receptacle 24 constructed of any suitable material is suspended from the shaft 8 that rotates freely within said receptacle, burnishers consisting of small 85 balls 25 of any suitable material, as hardened steel, and of any suitable number being loosely deposited within the receptacle, as shown in Figs. 1 and 2 of the drawings. The receptacle may have overturned lips 26 90 if desired for retaining the balls or burnishers in the receptacle. This receptacle may be of any suitable form and shape to perform the function required, and its walls may be constructed in various ways, as 95 shown herein the bottom 27 being corrugated to prevent the balls from rolling too freely from side to side, although it is not essential that such means shall be provided.

In operation it is intended that the articles, as spoons 21, shall be subjected to the rolling action of the balls, this action being caused by the movement of the articles in the mass of balls or by a movement of the receptacle causing the balls to pass in rolling contact with the articles. In the form of construction shown herein the receptacle is given a rocking movement on the shaft 8 as by means of a pitman 28 secured at one end to the receptacle and at the other end to 110

a rotating disk 29 and operated from any suitable source of power. It will be understood however that this rubbing action of the balls upon the articles may be obtained 5 in various ways and that the invention as embodied in the claims herein is not confined to a structure as herein shown and described for determining this result.

As a means for increasing the pressure of 10 the balls upon the articles being burnished, magnetic force may be applied to the balls in any suitable manner, one form of device being shown herein and consisting of a magnet 30 secured to the bottom of the receptacle in such manner that its force may be transmitted to the balls within the receptacle, such force being generated as by means of a current of electricity from a battery 31 or other suitable source of electric energy.

20 The apparatus shown herein embodies a single set of holders located within the receptacle, but our improvement contemplates the employment of holders in such number of sets as may be desired, and when magnetic force is used, which however is not at all times necessary, the means for obtaining that force may be of any suitable construction that will attain the desired end.

While we have shown and described herein 30 in a satisfactory construction of apparatus embodying our invention embodied in the following claims it is to be understood that we do not confine the invention to an apparatus so constructed.

35 We claim—

1. A receptacle having a bottom arranged to assume different angular positions with respect to a vertical plane as the receptacle is moved, balls located within the receptacle, 40 a holder projecting into the receptacle, means for securing an article in the holder, and means for moving the receptacle.

2. A receptacle having a bottom arranged to assume different angular positions with 45 respect to a vertical plane as the receptacle is moved, balls located within the receptacle, a holder projecting within the receptacle, means for retaining the holder against movement, and means for moving the receptacle.

50 3. A shaft, a receptacle suspended from the shaft and having a bottom arranged to assume different angular positions with respect to a vertical plane, a holder arm projecting from the shaft, balls located in the 55 receptacle, a holder supported by said arm, and means for causing a movement of the receptacle.

4. A shaft, a receptacle suspended from the shaft, balls located within the receptacle, 60 a holder arm projecting from the shaft into

the receptacle, a holder supported by said arm, means for retaining the shaft against movement, and means for rocking the receptacle on said shaft.

5. A receptacle, a shaft, holder arms projecting in opposite directions from said shaft and adapted to be located in said receptacle, holders supported by said arms, means for rotating the shaft to locate said holders successively in the receptacle, and balls located 70 within the receptacle.

6. A shaft, holder arms projecting in opposite directions from the shaft, holders supported by said arms, a receptacle suspended from the shaft to receive said holders, balls located in said receptacle, means for rocking the receptacle on the shaft, and means for holding the shaft against rotation.

7. A receptacle, balls located in the receptacle, a holder arm projecting into the receptacle, a holder supported by said arm, means for imparting movement to the holder and the balls one with respect to the other, and means for supplying magnetic force to 85 the balls.

8. A shaft, a receptacle suspended from the shaft, a holder arm projecting from the shaft into the receptacle, a holder supported by the holder arm, balls located within the receptacle, means for supplying magnetic force to the balls, and means for imparting movement to the holder and receptacle one with respect to the other.

9. A shaft, a receptacle suspended from the shaft, holder arms projecting from the shaft in opposite directions and adapted to be located in the receptacle, balls located in the receptacle, means for supplying magnetic force to the balls, means for rocking 100 the receptacle, and means for holding the shaft against rotation.

10. A receptacle, balls in the receptacle, means for supporting an article to be burnished in the receptacle, means for imparting movement to the holder and balls, one with respect to the other, and means for supplying magnetic force to the balls.

11. A shaft, a receptacle suspended from the shaft and having a curved bottom, balls 110 located in said receptacle; a holder projecting into the receptacle, means for securing an article in the holder, means for retaining the shaft against movement, and means for vibrating the holder on said shaft. 115
